UNITED STATES PATENT OFFICE.

CHARLES STUTZ, OF BROOKLYN, NEW YORK.

BRANDING-MACHINE FOR CIGAR-BOXES.

No. 796,771.

Specification of Letters Patent.

Patented Aug. 8, 1905.

Application filed March 9, 1904. Serial No. 197,281.

To all whom it may concern:

Be it known that I, CHARLES STUTZ, a citizen of the United States, and a resident of Brooklyn, in the county of Kings and State of New York, have invented certain new and useful Improvements in Branding-Machines for Cigar-Boxes, of which the following is a specification.

My invention relates to branding-machines for cigar-boxes and the like, and its novelty consists, primarily, of the construction and adaptation of the parts whereby the branding-plates are heated and applied to the work in a manner productive of superior results, as will be more fully hereinafter pointed out.

In the drawings, Figure 1 is a central vertical section of a machine embodying my invention. Fig. 2 is a front elevation thereof, some of the parts being cut away to show concealed parts. Fig. 3 is a rear view of the branding-plate support and heating device. Fig. 4 is a side elevation, and Fig. 5 is a transverse section, of the branding-plate support. Fig. 6 is a side elevation, and Fig. 7 a front plan view, of the front flame-support pipes.

My invention will be best understood by saying that it consists, primarily, of means for heating the front of the branding-plate by a live intensely-hot flame and at the same time heating the rear of the branding-plate with another flame of a lesser degree of heat. The branding-plate is mounted upon a mechanism similar to a bed-and-platen printing-press designed for jobwork, the branding-plate taking the place of the ordinary type or printing-plate and the heating-burner taking the place of the inking-rollers. The changes in the mechanism to accommodate it to the novel purpose for which it is employed will be best understood from this preliminary statement.

In the drawings, 20 represents the supporting-frame of the device, braced with suitable cross-pieces 21 and provided with a fly-wheel 22, a main shaft 23, and a pulley 24 mounted thereon and driven from a source of power. (Not shown.) The pinion 26 on this shaft meshes with the gear 27, which in turn actuates the shaft 41, on which is mounted a crank-disk 70 and a cam 51, the purposes of which will presently appear.

An upwardly-extending bracket 28 on each side of the device affords bearings for the shafts 23 and 41. To the front portion of this bracket is secured in any suitable man-

ner a vertical bed-plate or diaphragm 40, to which is secured in front the branding-plate 42. This branding-plate is immediately supported upon the intermediate heating-plate 43, which is provided with vertical channels 43^a and horizontal channels 43^b, in the former of which a series of gas-pipes 44 45 46, communicating with a common supply-pipe 47, are located. The supply-pipe in turn receives gas from a valve-controlled coupling 48 and a flexible supply-pipe 49, connected to the source of supply. The pipes 44, 45, and 46 are each supplied with apertures 44^a to permit of the escape of the gas in jets for ignition, the whole framework forming the means of heating the back of the branding-plate. The heating-plate 43 supports the pipe 47 by means of brackets 47^a and is mounted on the bed-plate 40 by means of screw-bolts 40^a, passing therethrough and separated from said bed-plate by a sheet 40^b. At the intersection of the grooves or channels 43^b with the channels 43^a the latter are provided with a deepened portion 43^c, which not only makes the plate thinner at this point, but allows a freer circulation of the flame and more effective heating of the said plate.

The means for moving the work against the branding-plate are as follows: The disk 70 is connected with a connecting-rod 71, which in turn is connected to a shaft or hinge 72, adapted to oscillate in suitable bearings 73, made integral with or secured to a table 74, adapted to rock on a rocking shaft 30, the rotation of the disk 70 communicating an intermittent rocking motion to the table 74. The work is placed upon this table 74 in the same manner as a sheet of cardboard or paper is placed upon the ordinary printing-press, and when the table is rocked forward the work is brought to bear against the branding-plate 42, which has been heated in a manner to be presently described, and the letters, figures, or other matter embossed upon the plate are thus impressed upon the cigar-box lid or other object to be branded.

It is obvious that the mechanism so far described is an operative device, the branding-plate being heated by the flames from the gas-burner back of it and the work being brought in contact with it by means of the oscillations of the plate 74. In practice, however, it has been found that branding-plates heated from the back are not brought to a sufficiently high temperature in front, where the metal must come in contact with

the work. In other words, the conductivity of the metal is not sufficient to transmit the heat from the back through the plate and maintain it at a temperature high enough to effect the purpose desired.

I have discovered that if a living flame be caused to impinge against the front surface of the branding-plate just prior to the time when the work is brought in contact therewith and if at the same time any loss of heat by the conductivity of the metal is prevented by heating the rear of the branding-plate the temperature produced on the surface of the embossings on the front of the plate is practically that of the impinging flame, and the result is that when the work is brought into contact therewith the surface of the wood is instantly and sharply seared or branded in a clear and efficient manner not possible by any other means known to me.

It is obvious that the flames caused to impinge upon the front of the branding-plate must be without carbon in suspension. In other words, they must be blue flames. They must also be intermittently supplied to the branding-plate in order to permit the work to be brought up against the latter. The means which I employ to accomplish this purpose are as follows: Suspended on each side of the machine and adapted to oscillate upon the shaft 41 is a framework 69, inclosing two long rods 143 and 144, around which are coiled springs. At the ends of these rods are blocks 145 and 146, passing transversely across the plate 40 and supported at each side by an upwardly-extending bracket 60, the front edge of which is provided with transverse slats 61, 62, and 63. Upon two of these slats 62 and 63 is mounted a front burner consisting of a supply-pipe 64, inwardly-projecting burners 65 65 65, supplied with air-mixing holes 66, a valve controlled connection 67, and a flexible gas-supply pipe 68. 50 is a curved rocking arm, I-shaped in cross-section, adapted to oscillate upon a rocking shaft 52 and connected at 53 with a link 54, which in turn is connected with a rod 55, secured to the frame 69. The cam 51, rotating and at the same time being brought into contact with the arm 50, imparts to the latter a rocking motion, which in turn is communicated to the frame 69 to oscillate the latter. This imparts a vertical motion to the blocks 145 and 146, which are kept in contact with the vertical plate 40 by means of the retractive force of the springs coiled around the rods 143 and 144, and in turn imparts a vertical reciprocating motion to the brackets 60 60, which carry the front gas-burners.

The motions of the mechanism are so timed that the brackets 60 60 are in front of the branding-plate, so that the flames may play thereon while the table 74 is depressed to receive the work. As the table is pulled

forward by the motion of the connecting-rod 71 the brackets 60 60 move vertically upward and by the time the work has been brought against the branding-plate are completely out of the way. Then as the table 74 moves back to place the front burner is reciprocated downward until it is again in front of the branding-plate to heat the latter.

It will be observed that in the embodiment of the invention shown in the accompanying drawings the work-carrier and the branding-plate have a relative pivotal or rocking movement, and also that while the actuating means for the movable burner have pivotal movement yet said burner is moved bodily instead of pivotally into and out of operative relation with the branding-plate.

It is obvious that wide modifications may be made in the details of the mechanism described without departing from one of the principles upon which it is based—namely, that the branding-plate must be subjected to a very high temperature on its face immediately prior to its being brought into contact with the work, and that the lowering of this temperature must be prevented by supplying it with heat in the rear, so as to make up for any loss due to the conductivity of the metal or the escape of the heat into the surrounding atmosphere.

As the particular embodiment of the invention shown in the accompanying drawings possesses many advantages other than that of heating the front and rear of the branding-plates, claims more and less restricted to said embodiment are made.

What I claim as new is—

1. A branding-machine, comprising a relatively movable work-carrier and branding-plate, means respectively heating the front and rear of said branding-plate, one of said heating means operating on said branding-plate during the branding operation and means by which the other of said heating means is moved relatively to said work-carrier and branding-plate between the branding operations.

2. A branding-machine comprising a relatively movable work-carrier and branding-plate, means for producing relative movement of said parts, means for heating the front of said branding-plate, means for moving said heating means into and out of operative relation with said branding-plate between the branding operations, and a heating means of lower intensity than that above mentioned, operating on the rear of said branding-plate during the branding operation.

3. In a branding-machine, the combination with a movable work-carrier, a branding-plate and means for moving said work-carrier toward and from said branding-plate, of a heating means for said branding-plate and means by which said heating means is

moved to and from said branding - plate through a path intersecting the path of movement of said work-carrier.

4. In a branding - machine, the combination with a movable work-carrier, and a fixed branding-plate toward and from which said work-carrier is moved, of a movably-mounted heating means for the branding - plate, means for moving said heating means across the path of movement of the work-carrier and into and out of operative relation with the branding-plate, and means for heating the rear of said plate.

5. In a branding - machine, the combination with a movable work-carrier, and a fixed branding-plate toward and from which said work-carrier is moved, of a movably-mounted heating means for the branding - plate, means for moving said heating means across the path of movement of the work-carrier and into and out of operative relation with the branding-plate, and means for heating the rear of said plate, said heating means for the front and rear of said plate being of different intensities.

6. In a branding - machine, the combination of a fixed branding-plate, a work-carrier, means for moving said work-carrier toward and from said branding - plate, a heating means between said branding - plate and work-carrier and means for moving said heating means relatively to said plate and carrier, into and out of operative relation with said plate, prior to the branding operation.

7. A branding-machine comprising a branding-plate and a work-carrier, one of which moves pivotally toward and from the other, a movable heating means for said branding-plate, and operating mechanism comprising a driving-shaft having connection with said work-carrier and heating means and moving the same through intersecting paths.

8. In a branding - machine, the combination of an oscillatory work-carrier, a branding-plate, means for heating the front of said plate movable toward and from the same across the path of movement of said carrier, means for heating the rear of said plate, said heating means for the front and rear of said plate being of different intensities, and devices for simultaneously oscillating said work-carrier from or toward the branding-plate and moving said movable heating means toward or from said plate.

9. In a branding - machine, the combination of an oscillatory work-carrier, a branding-plate, a movably-mounted heating means comprising a gas-burner adapted when in operative position to emit blue flames and to cause the same to impinge upon the front of said plate, means for heating the rear of said plate, and devices for simultaneously oscillating said work-carrier from or toward the branding - plate and moving said heating means toward or from said plate.

10. A branding - machine comprising a work - carrier and a branding - plate, one of which moves pivotally toward and from the other, a heating means for said branding-plate and devices for moving said heating means bodily into and out of operative relation with said branding-plate through a path intersecting that of the above-mentioned pivotally-movable part.

11. A branding-machine for cigar-boxes and the like, comprising a branding-plate, an oscillatory work - carrier, a reciprocatory heating means for the front of the branding-plate, devices for oscillating said carrier and reciprocating said heating means, and means for heating the rear of said plate.

12. A branding-machine for cigar-boxes and the like, comprising a branding-plate, an oscillating work-carrier, means for heating the front of said plate, means for moving said heating means out of the path of oscillatory movement of said carrier immediately prior to each branding operation, and means for heating the rear of said plate during the branding operation.

13. A branding-machine for cigar-boxes and the like, comprising a branding-plate, a bodily-movable heating means therefor, and mechanism for moving said heating means bodily into and out of operative relation with said branding - plate comprising pivotally-movable operating means and devices by which the heating means derives its said movement from pivotal movement of said operating means.

14. A branding-machine for cigar-boxes and the like, comprising a branding-plate, a bodily-movable heating means for said plate, and mechanism for moving said heating means, having a pivoted frame and means by which said heating means derives bodily movement from pivotal movement of said frame.

15. A branding-machine for cigar-boxes and the like, comprising a branding-plate, a movably-mounted means for heating the front of said plate, and means for moving the same, comprising an oscillatory frame, supporting devices for said heating means connected with said frame and reciprocated thereby, and means for oscillating said frame, comprising a rocking arm connected with said frame and a cam engaging said rocking arm.

16. A branding-machine for cigar-boxes and the like, comprising a branding-plate, a movably-mounted means for heating the front of said plate, and means for moving the same, comprising an oscillatory frame provided with rods, blocks attached to said rods, a bed engaged by said blocks, means connected with said blocks and carrying said heating means, springs connected with said blocks and holding the same against said bed and means for oscillating said frame.

17. A branding-machine for cigar-boxes and the like, comprising a branding-plate, a movably-mounted means for heating the front of said plate, and means for moving the same, comprising an oscillatory frame provided with rods, blocks attached to said rods, a bed engaged by said blocks, means connected with said blocks and carrying said heating means, springs connected with said blocks and holding the same against said bed, and means for oscillating said frame comprising a rocking arm connected with said frame and a cam engaging said arm.

18. A branding-machine for cigar-boxes and the like, comprising a branding-plate, an oscillatory work-carrier, a main shaft connected with said carrier, a reciprocating heating means for said plate and means for reciprocating the same connected with said main shaft.

19. A branding-machine for cigar-boxes and the like, comprising a branding-plate, a main shaft, an oscillatory work-carrier connected with said shaft, a reciprocating heating means for said plate, and means for reciprocating the same, comprising an oscillatory frame, supporting devices for said heating means connected with said frame and reciprocated thereby, and means operated by said main shaft for oscillating said frame.

20. A branding-machine for cigar-boxes and the like, comprising a work-carrier, a branding-plate, means for heating the front of said branding-plate, means for moving said heating means into and out of operative relation with said branding-plate, and means for supporting said branding-plate and heating the rear thereof, comprising a grooved plate, and heating means arranged in the groove of said plate.

21. A branding-machine for cigar-boxes and the like, comprising a branding-plate and a heating-plate to which the same is attached, said heating-plate having intersecting grooves deepened at the places of intersection, means arranged in said grooves for heating one side of said plate, means for heating the opposite side of said plate, and means for moving the last-named heating means toward and from said plate, and means for supporting the work being branded.

22. In a branding-machine for cigar-boxes and the like, a branding-plate, means for heating it from the rear, means for heating it to a greater extent at the front, comprising devices for causing blue flame to impinge upon the same, and means for bringing the work into contact with the front of the branding-plate immediately after such heating.

23. A branding-machine comprising a branding-plate, a relatively movable work-carrier and heating means, said heating means comprising devices for causing blue

flame to impinge on the front of the branding-plate, an operating-shaft and connections between said shaft and the work-carrier and heating means operating to move the same from said shaft relatively to each other and successively into operative relation with said branding-plate.

24. A branding-machine comprising a fixed branding-plate, a relatively movable work-carrying table and heating means in front of said branding-plate, said heating means comprising devices for causing blue flame to impinge on the front of the branding-plate, devices for moving said work-carrier and heating means intermittently and relatively to each other and successively into operative relation with said branding-plate, and means for preventing the escape of the heat from the branding-plate after being subjected to said flame.

25. In a machine of the class described, a fixed branding-plate, a blue-flame-supplying burner and means for intermittently bringing the same in front of the branding-plate, a work-carrying table movable relatively to said branding-plate and burner and means for bringing the table close to the branding-plate while the burner is removed therefrom, in combination with means for continuously heating the branding-plate from the rear.

26. A branding-machine comprising a work-carrier, a branding-plate, a heating means for the front of the branding-plate, and an operating-shaft and connecting devices for automatically moving parts intermittently and relatively to each other at predetermined intervals which causes the heating means and the work-carrier to be successively brought into operation relative with the branding-plate.

27. In a branding-machine, the combination with a work-carrier, a branding-plate, a main operating-shaft, and devices driven by said shaft and connected with one of said parts and operating to move the same toward and from the other, of means respectively heating the front and rear of said branding-plate, the rearward one of said heating means being operatively related to said branding-plate during the branding operation, and devices connected with the front heating means and operating to move the same automatically into and out of operative relation with said branding-plate between the branding operations.

Witness my hand this 23d day of February, 1904, at the city of New York, in the county and State of New York.

CHARLES STUTZ.
